MACHINE FOR DRILLING WINDOW SHADE ROLLERS

George A. Phinn, Pasadena, Calif.

Application July 6, 1953, Serial No. 366,135

8 Claims. (Cl. 144—93)

This invention relates to a machine for extending window shade rollers, and particularly to a machine for accurately supporting a wooden window shade cylinder in axial alignment with a drill bit. The end of the cylinder is then drilled along its axis, so that a dowel may be placed in the bored holes to two such cylinders and a combination cylinder of greater length provided.

Wooden shade rollers presently on the market are sold in a variety of relatively short standard lengths, so that when it is desired to form a short shade roller of non-standard length it is merely necessary to buy the next longer standard length and cut it to size. However, when it is necessary to form a relatively long shade roller it is customary to employ metal instead of wooden cylinders since no wooden shade roller cylinders of the longer lengths are presently available. Since the cost of a metal cylinder is several times that of a wooden cylinder of equal length, attempts have been made to extend wooden cylinders in such a way as to provide a combination cylinder having the necessary dimensions. This, however, necessitates the carrying out of extremely accurate drilling operations in order to form the axial end holes in which the dowel, which connects the two components of the combination cylinder, is placed. Where the end holes are not accurately drilled on the axes of the cylinders to be joined, a substantial wobble results which renders the extended cylinder unsuitable for use as a shade roller.

In view of the above factors characterizing the field of window shade rollers, it is an object of the present invention to provide a simple and inexpensive apparatus for forming axial end holes in wooden shade roller cylinders, the apparatus being highly accurate yet sufficiently simple in operation to permit its use by unskilled personnel in relatively small window shade companies.

A further object is to provide a novel means for holding a wooden window shade cylinder in axial alignment relative to a drill, portions of the aligning means being movable with the cylinder as it is advanced over the drill during the boring operation.

An additional object is to provide novel adjustment, bearing, and spring return means for expediting the drilling operation and rendering it more accurate.

These and other objects and advantages of the invention will be more fully set forth in the following specification and claims considered in connection with the attached drawing to which they relate.

In the drawing:

Figure 1 is a top plan view illustrating a shade roll drilling apparatus embodying the invention;

Figure 2 is a view along line 2—2 of Figure 1, partly in vertical central section and partly in elevation;

Figure 3 is a vertical transverse sectional view along line 3—3 of Figure 1 and as viewed in the direction of the arrows;

Figure 4 illustrates the abutting ends of an extended shade roller, the ends being joined by a dowel inserted in holes formed with the present apparatus; and

2

Figure 5 is a vertical transverse section along line 5—5 of Figure 1.

Referring to the drawing, the apparatus for extending wooden shade rollers is seen to comprise an elongated supporting base 10, drill means 11 mounted at one end of base 10 and extending longitudinally toward the other end thereof, slidable cylinder support means 12 mounted on the base 10 at the inner end of drill means 11, and stationary cylinder support means 13 mounted at the other end of base 10 and cooperating with slidable support means 12 to align the cylinder to be drilled. A typical wooden shade roller cylinder to be drilled is shown at 14 in Figures 1 and 2, and its connection to a corresponding cylinder 16 by means of a dowel 17 is shown in Figure 4, the dowel being inserted in axial end holes 18 formed in cylinders 14 and 16 in accordance with the invention.

The drill means 11 comprises an electric motor 20 the shaft of which is connected, by means of a chuck 21, with a relatively long straight drill 22. The drill 22 extends longitudinally of base 10 and is associated, at approximately its center, with a thrust bearing 23 adapted to prevent axial drill displacement when the cylinder 14 is forced against the twisted bit or cutting end of the drill during the boring operation. The thrust bearing is shown as taking the form of a support block 24 which is anchored on base 10 and provided on one of its faces, remote from motor 20, with a thrust boss 26. Support block 24 and thrust boss 26 are apertured to loosely receive the drill as shown in Figure 2, and thrust collar 27 is suitably mounted on the drill shank closely adjacent the thrust boss. The thrust of the drill in the direction of motor 20 is then taken by rubbing contact between the cooperating thrust collar 27 and thrust boss 26, and there is consequently no tendency to damage the motor 20.

The slidable cylinder support 12 comprises an upright block 29 which is anchored on a horizontal carriage plate 30 adapted to slide on base 10 between L-sectioned guides 31 and 32 illustrated in Figure 3. Block 29 is formed with a cylinder-receiving opening 33 having a conical wall 34 which opens out in the direction of stationary cylinder support 13. Opening 33 is in axial alignment with drill 22 and is of such size that various diameters of cylinders 14 will engage conical wall 34 intermediate its base and inner edges, so that different sizes of shade roller cylinders may be extended without the necessity of using separate and interchangeable support blocks. The guides or slides 31 and 32 are disposed parallel to drill 22 adjacent opposite edges of base 10, and are adapted to guide the carriage plate 30 and cylinder-receiving block 29 as it moves toward motor 20 under the impetus of an operator pressing on cylinder 14. A return spring 36, of the helical tension type, is mounted between carriage plate 30 and the stationary cylinder support 13 to effect return movement of the carriage and associated elements at the end of a drilling operation.

The slidable cylinder support means 12 further comprises a drill bearing block 37 mounted on the inner face of block 29 and centrally apertured, axially of drill 22, to receive and accurately locate the bit end of the drill. In order to accurately position the drill bit without injury to the bearing block or to the drill, suitable bushings 38 and 39 are mounted in the bearing block aperture as shown in Figure 2. Drill bearing block 37 is normally adjusted so that the cutting end of drill 22 will lie along the axis of conical opening 33 and will drill a hole 18 at precisely the axis of cylinder 14 when the slidable means 12 are shifted from the solid line to the dashed line position shown in Figures 1 and 2.

The stationary cylinder support means 13 comprises a pair of upright V-jaws 41 and 42 mounted on opposite edges of an oblong pivot block 44, the latter being in

turn mounted on the upper surface of an adjustment plate 46 lying on base 10. The pivotal connection between pivot block 44 and adjustment plate 46 takes the form of a vertical bolt 47 passing axially through the pivot block as shown in Figure 2. The V-jaws 41 and 42 are identical in shape and size, and are disposed symmetrically about both the major and minor axes of pivot block 44. Furthermore, the V-jaws lie in parallel planes which are perpendicular to the minor pivot block axis, with the angular notch 48 of each V-jaw opening toward the minor axis so that the jaws may fit over the cylinder 14 to maintain it in alignment. Referring to Figure 5, each of the notches 48 comprises two edges 49 which diverge at equal angles to a horizontal plane passing through the apex at which the edges meet, the angle between each edge and the horizontal plane being on the order of forty-five degrees. The jaws are so mounted that the horizontal plane passing through the apexes of the jaw notches will also pass through the axis of conical opening 33 and of drill 22. It follows that when the jaws 41 and 42 are urged against opposite sides of the cylinder 14 as shown in Figure 1, the axis of the cylinder will be at the same elevation as the axis of conical opening 33 and of the drill. In order to urge the jaws into gripping relationship with the cylinder, a helical tension spring 51 is connected between one end of pivot block 44 and a post 52 on adjustment plate 46, the post 52 also serving as one end connection for the carriage return spring 36. It will be noted that the positioning of spring 51 is such that it opposes rotation of the pivot block to align cylinder 14 with the drill, for example in pivoting the cylinder from the solid line to the dashed line position shown in Figure 1, the V-jaws 41 and 42 then pressing against the shade roller to effectively hold it in place.

In the normal use of the shade roller extending apparatus, all of the parts are adjusted so that a precise axial bore is formed in the end of wooden roller 14. Thus, in normal operation the vertical axis of pivot bolt 47 for pivot block 44 passes through the axis of conical opening 33. In addition, the drill 22 lies in exact axial alignment with the conical opening and in the same horizontal plane as the apexes of jaw notches 48. However, to permit flexibility in the operation of the machine, the cylinder-supporting means 12 and 13 are provided with adjustment means permitting off center holes as well as holes at an angle to the cylinder axis. The adjustment means for slidable drill support 12 comprise a plurality of inwardly directed screws which are normal to and engage the various edge faces of drill bearing block 37. Screws 54 are threaded through suitable straps 56 which are mounted on block 29 and overhang the relatively small block 37. Through rotation of the various screws 54, the bit end of drill 22 may be vertically or horizontally shifted so that it no longer lies along the axis of conical opening 33 but instead is somewhat off center.

Also, it will be understood that screws 54 may be rotated in order to cause the cutting end of the drill to be perfectly centered relative to opening 33, despite any inaccuracy in the mounting of cylinder support means 12.

To provide for the adjustment of stationary drill support 13, the adjustment plate 46 is pivoted at its inner edge as shown in Figure 1, the pivot comprising a vertical screw 57. The axis of screw 57 is at a right angle to, and intersects, the axis of conical opening 33. The adjustment plate 46 may be pivoted on screw 57 through operation of a transversely extending adjustment bolt 59 which projects inwardly from a lug 61 on one edge of support 10 for threaded connection with a lug 62 on the adjacent edge of the adjustment plate. As indicated in Figure 5, the adjustment bolt 59 is formed with a collar 63, inwardly adjacent lug 61, to provide for pivoting of plate 46 in either direction upon selective rotation of the bolt. To aid in locking the adjustment plate in a desired position, a vertical screw 65 is inserted downwardly

through a transverse slot 66 in a horizontal plate 67 which overhangs the outer edge of adjustment plate 46, the screw being threaded into base 10 as indicated in Figure 2. Upon loosening of screw 65 and rotation of adjustment bolt 59 to pivot the adjustment plate 46 until pivot bolt 47 for block 44 is no longer directly beneath the axis of conical opening 33, the cylinder 14 will not be in axial alignment with the drill 22 when the inner cylinder end is positioned in the conical opening. The bore hole 18 in the cylinder end will then be directed at an angle oblique to the cylinder axis instead of extending along it as in the normal situation.

In the operation of the apparatus, let it be assumed that the various adjustment means are set to normal operating positions for shade roller extension, that is to say with the pivot axis 47 passing through the axis of conical opening 33, and with the shank and bit portions of drill 22 lying along the axis. Prior to the placing of a cylinder 14 in the apparatus, the components are in the solid line positions shown in Figures 1 and 2, with the pivot block 44 pivoted counterclockwise due to the operation of tension spring 51, and with the slidable cylinder support means 12 in the outer or retracted position due to the operation of tension spring 36. A shade roller 14 20 of any various diameters, such as fifteen-sixteenths inch, one and one-eighth inches, one and one-quarter inches, etc., is then inserted transversely of base 10 between V-jaws 41 and 42. The cylinder 14 is then rotated clockwise, as viewed from above in Figure 1, until its outer portion engages and is centered by jaw notch edges 49 of V-jaw 41, and its relatively inner portion similarly engages and is centered by the edges 49 of V-jaw 42. Clockwise rotation of cylinder 14 is continued, against the bias of spring 51, until the cylinder is in the axially 25 aligned position shown in dashed lines in Figure 1, after which the cylinder is slid until its inner end abuts the conical wall 34 of opening 33. When in this position the inner end of cylinder 14 is held, due to its engagement with the wall 34, in vertical and horizontal alignment 30 with drill 22. In addition, the outer end of the cylinder is held in vertical and horizontal alignment by the jaws 41 and 42, the cylinder then being axially aligned with the drill as desired. The operator then starts the motor 20, to effect rotation of drill 22, and he manually shifts 35 the cylinder 14 in the direction of the motor so that the end of the cylinder is pressed over the drill bit. During this operation, the slidable cylinder support 12 is shifted to the dashed line position shown in Figures 1 and 2. The cylinder support 13, however, remains stationary 40 while the cylinder 14 is slid through it, the tension spring 51 tending to maintain the V-jaws 41 and 42 in alignment condition during the operation. Similarly, the tension spring 36 tends to aid in centering the inner end 45 of cylinder 14 since it insures that the conical wall 34 will never move out of centering engagement with it.

A hole 18 being bored to the desired depth, the cylinder 14 is moved in the opposite direction to free it from the drill bit, the spring 36 then operating to return the carriage plate 30 and associated elements to their initial 50 positions. After the drilling operation is performed on two cylinders such as cylinders 14 and 16 shown in Figure 4, a dowel 17 is inserted in the cylinder 14 and the cylinder 16 is fitted over it. A relatively long combination cylinder is thus formed which may be used as a shade roller without possibility of wobble since the components 14 and 16 are in precise axial alignment.

While the particular apparatus herein shown and described in detail is fully capable of attaining the objects 55 and providing the advantages hereinbefore stated, it is to be understood that it is merely illustrative of the presently preferred embodiments of the invention and that no limitations are intended to the details of construction or design herein shown other than as defined in the appended claims.

I claim:

1. A machine for use in extending shade rollers, which comprises a base, a drill connected at its shank end to a motor, slide means mounted on said base, a cylinder-supporting member provided on said slide means for movement longitudinally of said drill, said cylinder-supporting member having a conical opening formed therethrough adjacent the cutting end of said drill, said conical opening being in axial alignment with said drill and having its relatively large diameter base portion remote from said motor, a pivot member spaced from said cylinder-supporting member on the opposite side thereof from said motor, said pivot member being pivotable about an axis normal to and intersecting the axis of said drill and said conical opening, and a pair of V-jaws mounted on said pivot member and on opposite sides of said pivot member axis for engagement at axially spaced locations with opposite sides of a cylinder to be drilled, said V-jaws being shaped to cooperate with said cylinder-supporting member in maintaining said cylinder in axial alignment with said drill during movement of the cylinder toward said drill to form an axial end bore therein.

2. The invention as claimed in claim 1, wherein the notches of said V-jaws are formed with angularly related edges intersecting at apexes disposed in a common plane with the axis of said drill and of said conical opening, and wherein means are provided to bias said pivot member in a direction to cause pivoting thereof to maintain said V-jaws in engagement with said cylinder.

3. The invention as claimed in claim 2, wherein the intersecting edges of each of said V-jaws lie in a plane parallel to a plane containing the intersecting edges of the other V-jaw, said parallel planes being parallel to said pivot member axis and equally spaced on opposite sides thereof.

4. The invention as claimed in claim 3, wherein said V-jaws are disposed symmetrically relative to a plane containing said pivot member axis and perpendicular to said parallel planes.

5. A machine for use in extending shade rollers, which comprises a base, a drill journaled on said base and connected at its shank end to a motor, carriage means mounted on said base for movement longitudinally of said drill, a cylinder-supporting member provided on said carriage means for movement therewith, said cylinder-supporting member having a conical opening formed therethrough adjacent the cutting end of said drill and converging toward said motor, a pivot member spaced from said cylinder-supporting member on the opposite side thereof from said motor, said pivot member being pivotable about an axis normal to and intersecting the axis of said drill and said conical opening, a pair of V-jaws mounted on said pivot member and on opposite sides of said pivot member axis for engagement at axially spaced locations with opposite sides of a cylinder to be drilled, spring means to urge said V-jaws into gripping engagement with said cylinder, and spring means to effect return movement of said carriage means at the completion of a drilling operation.

6. A machine for use in extending blade rollers, which comprises a motor, a drill mounted in said motor for rotation thereby, centering means mounted substantially axially of said drill and being adapted to shift from adjacent the cutting end of said drill toward said motor to encompass said drill, said centering means including means to define at least a portion of a conical surface of revolution converging toward said motor, a pivot member spaced from said centering means on the oppo-

site side thereof from said motor, said pivot member being pivotable about an axis normal to and intersecting the axis of said drill, a pair of jaws fixedly mounted on said pivot member and on opposite sides of said pivot member axis for engagement at axially spaced locations with opposite sides of a cylinder to be drilled, and means to bias said pivot member to pivot the same about said axis in a direction to maintain said jaws in engagement with said cylinder.

10 7. A machine for use in extending shade rollers, which comprises a base, a drill connected at its shank end to a motor, slide means mounted on said base, a cylinder-supporting member provided on said slide means for movement longitudinally of said drill and being adapted to provide a bearing for the cutting end of said drill, said cylinder-supporting member having a conical opening formed therethrough adjacent said cutting end of said drill, said conical opening being in axial alignment with said drill and having its relatively large diameter base portion remote from said motor, a pivot member spaced from said cylinder-supporting member on the opposite side thereof from said motor, said pivot member being pivotable about an axis normal to and intersecting the axis of said drill and said conical opening, and a pair of V-jaws mounted on said pivot member for engagement at axially spaced locations with opposite sides of a cylinder to be drilled, said V-jaws being shaped to cooperate with said cylinder-supporting member in maintaining said cylinder in axial alignment with said drill during movement of the cylinder toward said drill to form an axial end bore therein.

20 8. A machine for use in extending shade rollers, which comprises a base, a drill connected at its shank end to a motor, slide means mounted on said base, a cylinder-supporting member provided on said slide means for movement longitudinally of said drill, said cylinder-supporting member having a conical opening formed therethrough adjacent the cutting end of said drill, said conical opening being in axial alignment with said drill and having its relatively large diameter base portion remote from said motor, a pivot member spaced from said cylinder-supporting member on the opposite side thereof from said motor, said pivot member being pivotable about an axis normal to and intersecting the axis of said drill and said conical opening, a pair of V-jaws mounted on said pivot member for engagement at axially spaced locations with opposite sides of a cylinder to be drilled, said V-jaws being shaped to cooperate with said cylinder-supporting member in maintaining said cylinder in axial alignment with said drill during movement of the cylinder toward said drill to form an axial end bore therein, and a thrust bearing provided on said base for cooperation with a collar on the drill shank to absorb the thrust created by pressing said cylinder against said drill during the boring operation.
